UNITED STATES PATENT OFFICE.

CHARLES H. FOLEY, OF SHERMAN, TEXAS.

GRADING-MACHINE.

1,075,774.

Specification of Letters Patent. Patented Oct. 14, 1913.

Application filed April 29, 1911. Serial No. 624,056.

To all whom it may concern:

Be it known that I, CHARLES H. FOLEY, a citizen of the United States, residing at Sherman, in the county of Grayson and State of Texas, have invented a new and useful Grading-Machine, of which the following is a specification.

This invention relates to an improvement in grading machines, the primary object of 10 the invention being the provision of a motor driven grading machine, provided with means for driving the grading drum at a fixed speed, means for driving the main drive wheels at a variable speed, and means 15 for adjusting the axis of the drive wheels whereby the grading wheel may be brought closer to or move farther away from the surface to be acted upon.

A further object is to provide a grading 20 wheel or drum, which may be used for grading, tamping and as a roller, the frame of the machine being so mounted as to, if desired practically place all of the weight upon the drum when used as roller so as to elevate the traction wheels above the ground, thus permitting the roller to act as a traction wheel to propel the machine and at the same time concentrate the weight at the desired point.

25 A further object is to provide a grading machine having dirt receiving and delivery mechanism, which is operable from the motor through the medium of the grader drum, thus insuring a uniform speed relation between the drum and said mechanism.

With the foregoing and other objects in view which will appear as the description proceeds, the invention resides in the combination and arrangement of parts and in the 40 details of construction hereinafter described and claimed, it being understood that changes in the precise embodiment of the invention herein disclosed can be made without departing from the spirit of the invention.

45 In the drawings:—Figure 1 is a side elevation of the complete machine, the rear conveyer belt being shown in cross section. Fig. 2 is a view taken from the opposite side of the machine, the rear wheels being in their lowest position and the grading drum, acting as a roller. Fig. 3 is a top plan view of the machine, the rear conveyer belt being broken away. Fig. 4 is an end view of the grader drum showing the details of construction thereof, and the detachable fastenings for the plows. Fig. 5 is a transverse

section on line α — α , Fig. 4. Fig. 6 is a detail view illustrating the means for elevating or lowering the frame to regulate the positioning of the grading drum relatively to the surface traversed.

5 Referring to the drawings, the numeral 1 designates the main frame of my machine, which has suitably mounted in the forward end thereof, the pivoted yoke 2, carrying the steering roller 3, while extending rearwardly from said yoke, is a frame 4, to which are connected the cables 5, forming with the drum 6, and steering wheel 7, the steering gear of this machine.

6 In the rear of the frame, are journaled the two drive wheels 8, the mounting of which will be later described, but which are so mounted as to support the rear end of the machine. The boxes 9 carry the axle of the 75 said wheels 8, and by means of the feed screws 10, and hand wheels 11, the said boxes 9 may be adjusted relatively to the frame of the machine, the purpose of which will presently appear.

7 Mounted in the forward portion of the frame, to the rear of the forward roller, is the motor 12, which may be either operated by steam, or of the explosive type. This motor's drive shaft 13, carries at its ends the 80 two balance or fly wheels 14 and 14', which through the medium of the bevel gears a and b , transmit motion to the two short shafts 15 and 15', respectively, said short shafts being journaled to the sides of the 85 frame and operating the grading drum 30, through the medium of the small bevel gears 16 and 16', and the gearing 31 and 31', of said drum. By this means the grading drum 30 is revolved, and as the same is 90 geared to the engine shaft 13, the speed of the grading drum is regulated directly by the speed of said engine.

95 The shaft 15', is provided with a sprocket wheel 17, which by means of the chain 18 and sprocket 19, transmits motion to the shaft 20, which is journaled upon one side of the frame of the machine, and is provided with the variable speed mechanism 21, operated by means of the actuating rod 21', 100 whereby the small bevel gear 22, will operate the gear 23 and the shaft 24, at varying speeds thus permitting the traction wheels to be driven at a rapid or slower rate while the drum 30 is driven at a fixed speed, 105 the adjustability of the carrying wheels to the main frame, regulating the depth of cut 110

of the teeth 47 of the drum 30, so that a light or heavy cut may be made while the machine is traveling over the ground at a slower or faster speed as desired. This feature is a very important feature, in view of the fact that it is often desired to slow the machine when a deep cut is desired or the ditching machine is cutting through a harder surface. By this means the motor 5 drives the rear wheels at varying speeds according to the manipulation of the variable speed mechanism while the drum 30 is rotated at all times at a fixed speed according to the speed of the engine and the gearing 10 therebetween. This shaft 24 carries the sprocket wheels 25, the chains 26, transmitting power therefrom through the large sprockets 27, of the rear drive wheels 8, said drive wheels being provided with the gripping or friction strips 28, and having their shaft journaled in the lower end of the 15 swingingly mounted brackets 29, thus permitting the rear drive wheels to be adjusted, relatively to the main frame, without affecting the operation of the chains 26, the said brackets having the same axis as the shaft 24.

Meshing with the gearing 31, of the drum 30, is a small bevel gear 32, whose shaft 33, 20 is journaled upon the side of the main frame and extends rearwardly to transmit power to the dirt conveying belts 37 and 43, respectively. To accomplish this, the small bevel gear 34, upon the shaft 33, meshes with the 25 large bevel gear 35, mounted upon the transverse shaft 36, which through the medium of the drum 36', carried thereby transmits motion to the rearwardly moving conveyer belt 37. The forward end of this belt is 30 mounted upon the shaft 38 and drum 39, and is disposed below the main frame and within the same, just to the rear of the grading drum, whereby dirt lifted by said grading drum is dumped upon the conveyer belt 37, and its transverse strips 37' prevent the 35 dirt from falling, so that the said dirt is carried inclined upward and dumped upon the conveyer belt 43, to be carried away from the machine, or conveyed into 40 dump wagons. The bracket 40, secured to the underside of the main frame of the machine, supports the shaft 38, of the conveyer belt 37, thus holding the lower end of the conveyer belt 37 at the same relative position 45 to the grading drum 30.

By means of the gear 35 and the small gear 41, the shaft 42 is revolved to actuate the crosswise dirt receiving and conveying belt 43.

60 As shown in Figs. 4 and 5, the grading drum 30, consists of the castings or spiders 44, to the outer ones of which are attached the gearings 31, and the steel cylindrical drum 45, which is provided with the irregularly shaped openings 46, therein for the re-

movable insertion and fastening of the grading plows 47, whose shank 48, enters said openings 46, and is locked therein by means of the nut 49.

When it is desired to use my machine for 70 rolling entirely, the plows are moved from the drum 30, and the belt 37 is also removed; and the rear drive wheels adjusted, as in Fig. 2, to bring the drum 30 into contact with the surface to be rolled. Should the 75 machine be used for tamping, the plows are removed and tamping feet inserted in the drum 30, in the same manner as the plows 47.

It is evident from the foregoing description taken in connection with the drawings, 80 that a machine adapted for rolling lands, and roads, and grading and tamping road surfaces is provided, the machine being so constructed that the grading drum may be 85 easily and quickly adjusted for the desired cut; and further that the grading drum may be operated at a regular or fixed speed, whereas the driving mechanism, although employing the same motor power, may be 90 varied, as the work may require.

When it is desired that the weight of the machine be concentrated upon the drum 30, the hand wheels 11 are rotated so as to lift the traction wheels above the surface and consequently lower the drum 30, the wheel 3 and the drum 30 being the only rolling members in engagement with the ground at that time, thus converting the drum 30 into a traction means, and as before stated concentrating the full weight of the machine or nearly so, upon the roller 30. This is especially desirable when grading roads when it is not desirable to cut the surface with the traction spuds carried by the traction wheels. 100

By constructing a machine according to the present invention, an exceedingly light frame and traction means is provided, and by reason of the adjustable feature at the 110 forward end and of the rear traction wheels of the machine, the roller or drum 30 may be elevated as in Fig. 1 or lowered as in Fig. 2, but where it is desired as above stated, to provide a roller entirely, 115 the traction wheels are elevated so as not to contact the surface, and at which time the said wheels are disconnected from the motor so as to remain idle.

One of the salient or cardinal features 120 of the present invention resides in the fact that the lower or receiving end of the inclined conveyer belt 37 stands below the back of the drum 30 and slightly below a plane tangent to the bottom of the said 125 drum, whereby the lower end of the conveyer belt 37 serves as a scoop to receive the material loosened by the grading drum. A mouth will be provided between the lower end of the conveyer belt 37 and the grading 130

drum, through which the teeth of the grading drum pass, and in order that the material may be effectively lifted onto the upper run of the conveyer belt 37, both by the 5 scooping action of the lower end of the belt 37, and the rearward throw given the material by the grading drum. The frame 1 embodies side beams which carry the grading drum 30 therebetween, the rear driving 10 wheels 8 being adjustably connected to the said beams, whereby the beams may be adjusted vertically to vary the relation of the grading drum and lower end of the conveyer belt 37 with the soil. The conveyer 15 belt 37 is disposed between the driving wheels 8, so that it will be apparent that the material is elevated between the rear driving wheels to the transverse conveyer belt 43. The brackets 40 are in the form of 20 hangers or pendants suspended from the side beams of the frame 1, the drum or roller 39 for the lower end of the conveyer belt 37 being of relatively small diameter, in order that the lower end of the said conveyer belt may properly wedge under the material loosened by the grading drum. The drum or roller 36' for the upper end of 25 the conveyer belt 37 is of relatively large diameter, in order to space the upper and lower runs of the conveyer belt considerably 30 apart, it being observed that the axle of the rear driving wheels passes between the upper and lower runs of the conveyer belt 37 in order that the said axle may be ad-

justed vertically between the upper and 35 lower runs of the conveyer belt 37 relative to the side beams of the frame 1. The hangers or pendants 40 maintain the shaft 38 and its drum or rollers 39 at the proper position below the back of the grading 40 drum 30, and below a plane tangent to the bottom of the grading drum, in order that the aforesaid results will accrue in the use of the machine.

What is claimed, is:—

In a grading machine, a frame embodying side beams, rear driving wheels, an axle for the driving wheels adjustably connected to the respective beams, a grading drum carried by the beams in advance of the driving wheels, hangers carried by the beams, a roller of relatively smaller diameter carried by the hangers below the back of the drum and slightly below a plane tangent to the bottom of the drum, a roller of relatively 55 large diameter carried by the beams, a conveyer belt trained over the said rollers, the said axle extending between the upper and lower runs of the conveyer belt, and means for actuating the conveyer belt and grading 60 drum.

In testimony that I claim the foregoing as my own, I have hereto affixed my signature in the presence of two witnesses.

CHARLES H. FOLEY.
